UNITED STATES PATENT OFFICE.

EDWIN L. EDWARDS, FRANK A. FARWELL, AND FRANK O. WILEY, OF INDIANAPOLIS, INDIANA, ASSIGNORS TO UNIVERSAL SERVICE CORPORATION, OF INDIANAPOLIS, INDIANA, A CORPORATION OF INDIANA.

COIN-CONTROLLED LOCK.

Application filed July 7, 1923. Serial No. 650,155.

To all whom it may concern:

Be it known that we, EDWIN L. EDWARDS, FRANK A. FARWELL, and FRANK O. WILEY, citizens of the United States, residing at 5 Indianapolis, in the county of Marion and State of Indiana, have invented a new and useful Coin-Controlled Lock, of which the following is a specification, reference being had to the accompanying drawings and to 10 the letters and figures of reference marked thereon.

This invention relates to locking apparatus for doors of rooms or apartments, or 15 toilet rooms, requiring entrance fees, the invention having reference more particularly to a door lock that is designed to be operated by means of a coin to unlock the door.

An object of the invention is to provide a 20 simple and reliable coin-controlled lock suitable for use on doors, which shall be constructed of parts that may be manufactured at small cost.

Another object is to provide an improved 25 coin-controlled locking apparatus which shall be of such construction as to permit of slight modifications as to details so as to be adapted to different conditions of operation, and which shall prevent operation of 30 the lock by improper means.

A further object is to provide an improved coin-controlled lock and coin box combined which shall be of such construction as to permit compactness of mechanism 35 and provide for large coin capacity, which shall not have troublesome forms of springs, and which shall be durable and economical in use and not liable to become deranged nor troublesome in practical use.

40 With the above mentioned and other objects in view, the invention consists in a coin-controlled locking apparatus having operative mechanism of such design as to be readily operated and not greatly retarded 45 by frictional resistance, which mechanism shall control the admission of coins and permit the coins to pass by the force of gravity through the lock controlling means and into the coin box; and, the invention 50 consists also further in a novel locking bar and a novel coin chute, and in certain novel parts and combinations and arrangements of parts, as hereinafter particularly de-

scribed and further defined in the claims appended hereto.

55 Referring to the drawings,—Figure 1 is a front elevation of the new coin-controlled lock arranged on the outer side of a door, a fragment of the door and its frame being shown; Fig. 2 is a fragmentary section approximately on the line II—II on Fig. 1, on an enlarged scale; Fig. 3 is a fragmentary edge view of the door and the improved lock applied thereto; Fig. 4 is an enlarged sectional elevation of the improved 60 locking apparatus approximately on the line IV—IV in the Figure adjacent thereto; Fig. 5 is a transverse section approximately on the line V—V in Fig. 4, a portion being broken away; Fig. 6 is a fragmentary view 65 similar to the upper portion of Fig. 4; but on a smaller scale and showing different parts in relatively different positions, the coin chute being in section; Fig. 7 is a horizontal section approximately on the line 70 VII—VII in Fig. 6, including a portion of the door; Fig. 8 is a fragmentary view 75 showing portions of Fig. 4, to illustrate the manner of preventing the entrance of a coin when one coin is already in the coin chute; Fig. 9 is a fragmentary view, as on the line 80 IX—IX in Fig. 8 showing particularly one side of the coin chute; Fig. 10 is a fragmentary sectional elevation similar to Fig. 6 85 but with the coin chute in a relatively different position, the section being on the line X—X in Fig. 7; Fig. 11 is a fragmentary view similar to Fig. 6 but with different parts in relatively different positions; Fig. 12 is a fragmentary horizontal section of 90 the door and its frame and the top of the lock casing partially broken away to clearly show the connection of the lock bar and its keeper as preferably constructed; Fig. 13 is a fragmentary sectional elevation on the 95 line X—X in Fig. 7; Fig. 14 is a fragmentary horizontal section of the door and its frame and the top of the lock casing partially broken away to illustrate a modified lock bar and keeper therefor; and, Fig. 15 100 is a fragmentary horizontal section of the door and its frame and the top of the locking case, partially broken away to show another modified locking bar and keeper therefor adapted for an in-swinging door. 105

Throughout the different figures of the

drawings similar reference characters indicate corresponding elements or features of construction herein referred to in detail.

For descriptive purposes in the drawings a fragmentary door frame is shown; the numeral 1 indicates one side of the frame to which the door 2 is to be locked, and the numeral 1' indicates the opposite side of the door frame to which the door is connected by 10 means of hinges 3. The coin-controlled lock as preferably constructed has a base plate or back wall 4 which is secured by means of screws 5 to the outer side of the door, and constitutes a part of the lock casing. The 15 upper portion of the base plate has a recess 6 in the rear portion thereof adjacent to the door, and the base plate has also a recess 7 adjacent to the edge of the door. The lock casing includes a removable part which comprises a front plate 8, side plates 9 and 10, a top plate 11 having a lip 12 that extends into the recess 6, the top plate normally resting upon the top of the base plate 4, and a back plate 13 fixed to the lower portion of the side 20 plates 9 and 10, the plate 13 being secured directly to the door by means of screws 14. The top plate 11 has a suitably located coin slot 15 arranged transversely therein, and preferably also a guide hood 16 to receive a 25 coin uprightly and guide it to the slot.

Locking mechanism comprises preferably a stub shaft 17 fixed to the base plate 4 adjacent to the lower portion thereof and in proximity to the casing side 10, and a hub 30 35 18 is rotatively arranged on the shaft and has a counter-bore 19 in the outer end thereof receiving the head 20 of a screw 21 inserted in the shaft and retaining the hub on the shaft. An escutcheon plate and collar 22 is 40 fixed on the front plate 8 and rotatively supports a spindle 23 having a transverse key projection 24 on its inner end that is removably inserted in slots 25 in the end of the wall of the hub 18, the outer end of the spindle having a handle 26 fixed thereon. A 45 novel movable coin chute is provided which comprises a main plate 27 that is fixed at its lower end to the hub 18 and extends upward, two sides 28 and 29 fixed on the main plate, and a front plate 30 fixed to the sides to provide a chute of the required dimensions to permit the desired coin to pass through it, the front plate extending upward slightly beyond the sides and having a 50 curved guide 31 fixed thereon that projects in the direction away from the main plate and slightly downwardly, being arranged so as to be carried over the coin slot but permitting a coin to pass from the slot into the 55 coin chute when the latter is in vertical position below the slot. The main plate of the coin chute has a recess 32 in its edge that is adjacent to the base plate 4, the side 28 being correspondingly cut away, and the plate 60 27 has a slot 33 extending downward from

the top thereof. The front plate 30 has a slot 34 arranged opposite to the slot 33 and it has also a recess 35 corresponding to the recess 32. The hub 18 has an arm 36 fixed thereon to which a coil spring 37 of suitable length is connected, the spring being connected to a stud 38 fixed to the base plate 4, the spring being strained to yieldingly hold the coin chute against a stop pin 39 secured to the base plate. The base plate has also 75 another stop pin 39' to stop the movement of the coin chute when tilted over from the stop pin 39.

A novel lock bar 40 is provided which is pivotally connected adjacent to one end 80 thereof to the stub shaft 17 between the base plate 4 and the inner end of the hub 18 and extends nearly to the casing side 9 which is adjacent to the edge of the door, and it has an arm 41 fixed thereto that extends upwardly from the shaft. The upper end of the arm has a shoulder 42 to support a coin in the upper portion of the chute, and the arm has also a lateral projection 43 to be engaged by the coin whereby to move the arm and thereby tilt the locking bar, for unlocking the door by means of the coin when the arm is forced back and is stopped against the stud 38, and the arm normally rests against a stop block 44 which is secured to the base 95 plate 4 and preferably extends partially across the top of the arm and the back of the coin chute.

An improved shutter is provided which comprises a plate 45 movably arranged 100 under the top plate 11 of the casing and preferably has a supporting flange 46 by which it is mounted on the base plate 4, the flange having longitudinal slots 47 therein receiving retaining and guiding screws 48 105 which are screwed into the base plate. The shutter is stopped in its movements against the side plates 9 and 10 of the casing. The shutter plate 45 has a coin slot 49 in the forward edge thereof that registers with the slot 15 when the shutter is stopped against the casing side 9, to permit a coin to pass into the coin chute. The front portion of the shutter plate 45 has a downward extending arm 50 at a suitable distance from the slot in the plate and it has a finger 51 that extends towards the upper portion of the coin chute and may be received into the slots 33 and 34, being arranged to be engaged by a coin in the chute to slide the 110 shutter over so as to close the coin slot 15. The flange of the shutter has a stud 52 thereon whereby to move the shutter over to permit entrance of a coin at proper times. An elastic finger 53 is mounted as a tension 115 spring on the base plate 4 and extends against the face of the flange 46 to slightly retard movement of the shutter so that it may not be accidentally jarred from its proper position by slamming the door. 120

The shutter plate 45 has downward extending fingers 54 and 55 thereon to operate a registering counter.

A spindle 56 is rotatively arranged in the door and extends through the base plate 4 and also into an escutcheon plate 67 arranged on the inner side of the door, and it has a suitable handle 58 connected thereto in the escutcheon plate. The inner end 10 of the spindle is supported in a frame bracket 59 secured to the base plate 4. A lever is secured to the spindle and has an arm 60 extending upward and an arm 61 extending downward, the latter having a stud 62 fixed thereon. The upper arm 60 extends partially over the flange 46 and may be moved into engagement with the stud 52 to move the shutter to open position. The front plate 8 of the casing has a hollow cylindrical bearing 63 fixed thereto in which a key cylinder 64 is rotatively arranged, which being of conventional type requires no further description, and the inner end 15 of the cylinder has an arm 65 fixed thereto that may be swung against the stud 62 whereby to move the lever arm 61 and cause operation of the arm 60. This enables the proprietor to unlock the door by means of a key without requiring the use of a coin.

A bracket 66 is secured to the base plate 4 and supports a suitable counter 67 that has an operating-shaft 68 which is provided with an arm 69 that extends between the fingers 54 and 55 to operate the counter in synchronism with the movement of the shutter. The side 9 of the casing has a window 70 through which to inspect the counter and ascertain the results of its operations.

The lower end of the lock casing being open, a coin box is removably inserted therein and comprises a bottom 71, front and back plates 72 and 73 and side plates 74 and 75. A cross bar 76 is secured to the front and back plates 72 and 73 whereby to secure the coin box in place. A hollow bearing 77 is secured to the front plate 8 of the casing and has a key cylinder 78 rotatable therein, the key cylinder being adapted to be locked against rotation as is well known, and the rear end thereof has an arm 79 secured thereto which has a hook 80 thereon to engage the bar 76, the front plate 72 being suitably recessed to clear the bearing 77.

The edge of the door has a recess 81 adjacent to the end of the lock bar and a guard plate 82 is secured to the edge of the door and extends across the recess. The inner side 60 of the door preferably has a guard plate 83 secured thereto that extends across the recess and has an aperture 84 therein to receive a keeper 85 which has a base plate 86 that is secured to the inner side of the door frame part 1. The keeper has an in-

clined end 87 to guide the lock bar up to the top of the keeper to permit the bar to fall by gravity into a notch 88 in the top of the keeper. Preferably a stop plate 89 is secured against the base plate 86 and supports a rubber buffer 90 against which the guard plate 83 may be directly stopped. The end of the lock bar and the keeper are effectually inclosed and can not be reached by an instrument in an attempt to improperly open the door.

In a slightly modified form a stop head 91 is secured to the inner side of the frame part 1 and supports a rubber buffer 92 and also a keeper 93 below the buffer, the keeper extending into and through the recess 81, the lock bar 40 having a relatively right angled projection 94 thereon that extends into the recess and engages the upper portion of the keeper, access thereto being prevented by the guard plate 82.

When the door 2 is designed to swing inward the lock bar 40 has a relatively right angled extension 95 that extends through the recess 81 and has a relatively right angled extension 96 thereon that projects behind the frame part 1, being inclosed in a suitable box 97 that is secured to the inner side of the door and receiving a keeper 98 through a suitable opening in its forward side to be engaged by the extension 96, the keeper having a base plate 99 that is secured to the inner side of the part 1. In each case the keeper proper is similar to the notched keeper 85. The design is such as to permit the lock bar to fall by the force of gravity into the notch in the keeper, but obviously the lock bar could if desired be provided with an actuating spring. Also the arm 60 could be provided with a spring to yieldingly hold it against the stop block 44 if desired.

In practical use, the mechanism being set as in Fig. 4, a coin 100 of standard dimensions is inserted through the coin slots 15 and 49 and gravitates into the coin chute until stopped upon the shoulder 42. If now the outer handle 26 is turned the coin is forced by the coin chute sidewise against the projection 43 and also against the finger 51, causing the arm 41 and the lock bar 40 to be tilted so that the bar is released from the keeper, the shutter being simultaneously shifted to close the coin slot 15, the shutter being stopped against the casing side 10 and retracts the operating arm 69 of the counter. Having released the lock bar from its keeper the door may be pulled open and the handle released. Upon release of the handle the lock bar drops to normal position, the coin chute and the arm 41 moves pivotally together, so that the coin is still supported upon the shoulder 42, letting the shutter rest against the casing side 10, thus preventing the insertion of another coin. The door hav-

ing been opened by a person, the room or compartment may be entered, after which the door may be drawn shut or closed by means of its spring hinges, causing the lock 5 bar to be automatically operated to lock the door in closed position. As the lock bar is forced up to the top of the keeper the arm 41 is retracted and carries the shoulder 42 from beneath the coin, permitting the coin 10 to fall into the coin box. When a person in the room or compartment desires to leave he turns the inner handle 58 which causes movement of the arms 60 and 61, the latter engaging the arm 41 and retracting the lock 15 bar, while the arm 60 is brought into engagement with the stud 52, which causes the shutter to be moved over to the casing side 20 so as to bring the slot 49 in the shutter below the slot 15, the movement of the shutter causing operation of the counter. When thus unlocked from the inside the door may be opened, after which the lock bar descends to normal position and is again operated to lock the door when the latter is closed, without disturbing other mechanism of the lock, the apparatus being set again as in Fig. 4 25 to permit another operation by means of a coin.

In case the proprietor desires to open the 30 door without the use of a coin and so as to not disturb the counter record, he inserts a special key in the key cylinder 64 and turns it so as to swing the arm 65 as indicated by broken lines in Fig. 13, the arm engaging 35 the arm 41 and retracting the lock bar without disturbing the coin chute and the shutter. Having operated the door it may be again closed and locked, the lock bar acting alone, and the door may be operated again 40 from the inside by turning the inside handle as before to retract the lock bar.

When the owner or proprietor desires to remove the coin from the coin box, he inserts a key in the key cylinder 78 and turns 45 it so as to disconnect the hook 80 from the cross bar 76, permitting the coin box to descend from the casing. The coin box is readily replaced to normal position and is again locked by swinging the arm 79 in the 50 opposite direction so that the hook 80 engages the lock bar 76.

What we claim as new is:

1. A coin-controlled lock having an upright coin chute and a normally horizontal lock bar provided with a pivotal support common to both permitting independent movement by either one, the lock bar having an upright arm fixed thereon to be moved by the chute by means of a coin, and means for actuating the coin chute. 55

2. A coin-controlled lock having a horizontally arranged lock bar pivotally supported at one end for upward retracting movement, the lock bar having an upright arm fixed thereto adjacent to the pivotal 60

support, the upper portion of the arm having a shoulder to support a coin to move the arm and thereby retract the lock bar, and means to force the coin against the arm to move the arm. 70

3. A coin-controlled lock having an upright coin chute and a lock bar provided with a horizontal pivotal support common to both permitting independent movement thereof, the upper portion of the chute having an opening in one side thereof, the lock bar being provided with an upright arm having a projection on its upper portion to be received into the opening in the chute and engaged by a coin in the chute to move the arm, and means for actuating the coin chute. 75

4. A coin-controlled lock having an upright coin chute and a lock bar provided at one end with a horizontal pivotal support common to both permitting independent movement thereof, the lock bar being provided at its pivotal support with an upright arm, the opposite end of the lock bar having a relatively angular portion to engage a keeper, the upper portion of the arm being arranged in proximity to the upper portion of the chute to be moved by the chute by means of a coin, and means for actuating the coin chute. 80

5. A coin-controlled lock including a stationary stub shaft, a lock bar pivotally connected to the shaft and having an operating-arm fixed thereto, a coin chute having a hub rotatively supported on the shaft to guide a coin to the operating-arm to thereby retract the lock bar, a handle connected to the hub of the chute to pivotally move the chute, and a shutter movably supported to operate above the chute and adapted to be actuated by means of the coin in the chute. 90

6. A coin-controlled lock including a pivoted lock bar having an operating-arm fixed thereto, a pivoted coin chute to guide a coin to the operating-arm whereby to operate it by means of the coin to retract the lock bar, a handle having operative connection with the coin chute to pivotally move the chute, a shutter above the coin chute and movably supported to be operated in one direction by means of the coin, and means for operating the shutter in the opposite direction and also moving the operating-arm to retract the lock bar. 100

7. A coin-controlled lock including a horizontally movable shutter, a normally horizontal pivotally movable lock bar having an upwardly extending arm fixed thereon to retractively operate the bar, and a laterally movable pivoted coin chute provided with a handle to operate it, the arm co-operating with the chute to enable the chute to simultaneously move the shutter and the arm directly by a coin in the chute. 110

8. A coin-controlled lock including a sta- 120

tionary stub shaft, a lock bar pivotally connected to the shaft and having an arm fixed thereto, the upper portion of the arm having a shoulder to support a coin and having also a lateral projection to be engaged by the coin to move the arm and thereby retract the lock bar, a coin chute arranged adjacent to the arm of the lock bar and having a hub rotatively supported on the shaft to guide a coin to the shoulder and the projection on said arm, and a handle connected to the hub of the chute.

9. A coin-controlled lock including a pivoted lock bar having an operating-arm fixed thereto, a pivoted coin chute to guide a coin to the operating-arm whereby to operate it by means of the coin to retract the lock bar, a handle having a spindle connected with the coin chute to pivotally move the chute, a shutter movably supported to be operated by means of the coin and having a stud thereon, a spindle rotatively supported and provided with a lever to be operated thereby, the lever having one arm to engage the stud and operate the shutter and having also a second arm movable to engage and operate the operating-arm of the lock bar, and a rotatively supported key cylinder having an arm movable into engagement with one of the arms of the lever and move it to operate the operating-arm of the lock bar.

10. A coin-controlled lock including a pivotally supported lock bar having an arm fixed thereto, the upper portion of the arm having a shoulder to support a coin and having also a lateral projection to be engaged by the coin to move the arm and thereby retract the lock bar, a coin chute arranged adjacent to the arm of the lock bar and pivotally supported to move either with or independently of the arm, the chute having a recess to receive the shoulder and lateral projection and having also a slot therein, the coin chute being open therethrough to guide a coin to the shoulder and the projection on the arm, means for actuating the coin chute, and a shutter movably supported above the coin chute and having a finger projecting towards the coin chute to be received into the slot therein and engaged and moved by the coin on movement of the chute to move the arm by means of the coin.

55 11. In a coin-controlled lock, the combination with a casing, of a stub shaft fixedly supported in the casing, a lock bar pivotally connected to the shaft and having an operating-arm fixed thereto, a coin chute pivotally supported by the stub shaft to carry a coin to the operating-arm and thereby move it to retract the lock bar, means for actuating the coin chute, a spindle rotatively supported in the casing, and a lever secured to the spindle and movable to the

operating-arm for actuating it to retract the lock bar without a coin.

12. In a coin-controlled lock, the combination of a lock bar and a coin chute, both pivotally movable and having a pivotal support common to both, the bar having an operating-arm fixed thereto and co-operating with the coin chute to enable the chute to move the operating-arm by means of a coin to pivotally retract the lock bar, and means for operatively moving the coin chute on its pivot.

13. In a coin-controlled lock, a lock bar horizontally arranged and pivotally supported at one end thereof, said end having an upwardly-extending arm fixed thereto, the upper portion of said arm having an upward-facing shoulder to support a coin and also a lateral projection thereon to be engaged by the coin, in combination with a movable coin chute supported on the pivot of the lock bar to guide a coin to said shoulder and force the coin sidewise against said projection and thereby move the operating-arm to pivotally move the lock bar retractively, and a handle for moving the chute.

14. In a coin-controlled lock, the combination with a casing, and a stub shaft supported in the casing, of a lock bar connected to the shaft and having an operating-arm fixed thereto, a coin chute arranged adjacent to the operating-arm to guide a coin thereto, the chute having a hub rotatively supported on the stub shaft, a spindle rotatively supported by the casing and detachably connected to said hub to move the chute in one direction, and a spring having connection with the casing and said hub to move the chute in the opposite direction.

15. In a coin-controlled lock, the combination of a shutter comprising a horizontal plate and a flange movably guided, the plate having a coin slot therein and having also an arm extending downward therefrom adjacent to one end of the plate and a finger extending horizontally from the arm parallel to said flange, a laterally-movable pivoted coin chute, means for moving the coin chute and a lock bar supported on the pivot of the coin chute and having an operating-arm co-operating with the coin chute to force a coin against said finger to operate the shutter by means of the coin and to enable the chute to operatively move the operating-arm also by means of the coin.

16. In a coin-controlled lock, the combination of a coin chute comprising a main plate having a rotatively-supported hub, the plate extending upwardly from the hub, sides fixed on the main plate and a front plate fixed on the sides, said plates having each a recess in one edge thereof and one of the sides having an opening corresponding to the recesses, means to turn said hub, and a lock bar pivot-

ally supported on the support of said hub and having an operating-arm extending upward adjacent to said chute and provided with a shoulder to be received in said recesses and the opening in said side and to be engaged by a coin in the chute, the operating-arm having also a lateral projection to be received in the recess in said main plate and to be engaged by the coin.

10 17. In a coin-controlled lock, the combination of a vertical coin chute and a horizontal lock bar having a pivotal support common to both, the lock bar having an upwardly-extending operating-arm to be pivotally moved by the chute by means of a coin to retract the lock bar, a horizontal movable shutter having a finger extending towards the coin chute to be engaged by the coin for

operating the shutter directly by the coin, the shutter having also two fingers thereon spaced apart, means for moving the coin chute in operative direction, a spindle rotatively supported and having a lever fixed thereto, the lever having an arm to retract the shutter and a second arm to engage and move the operating-arm of the lock bar, a key cylinder rotatively supported and having an arm to engage and move said second arm, and a supported counter having an operating-arm extending between said two fingers and operated and controlled thereby.

20 25 In testimony whereof, we affix our signatures on the 2nd day of July, 1923.

EDWIN L. EDWARDS.
